US00D986120S

(12) **United States Design Patent** (10) **Patent No.:** **US D986,120 S**
(45) **Date of Patent:** **** May 16, 2023**

(54) **HITCH MOUNT**

(71) Applicant: **Country Innovation and Supply, LLC**, Winder, GA (US)

(72) Inventor: **Keaton Smith**, Winder, GA (US)

(**) Term: **15 Years**

(21) Appl. No.: **29/785,207**

(22) Filed: **May 24, 2021**

(51) **LOC (14) Cl.** **12-16**

(52) **U.S. Cl.**

USPC **D12/162**

(58) **Field of Classification Search**

USPC D12/159, 160, 161, 162, 203, 223, 317,
D12/400; D21/777, 810

CPC B60D 1/363; B60D 1/241; B60D 1/30;
B60D 1/58; B60D 1/06; B60D 1/52

(57) **CLAIM**

The ornamental design for a hitch mount, as shown and described herein.

DESCRIPTION

FIG. 1 is a side view of the hitch mount in use;
FIG. 2 is a top side view of the hitch mount;
FIG. 3 is a left side view of the hitch mount;
FIG. 4 is a bottom view of the hitch mount;
FIG. 5 is a right side view of the hitch mount;
FIG. 6 is a front view of the hitch mount;
FIG. 7 is a back view of the hitch mount;
FIG. 8 is a cross section right side view of the hitch mount;
and,
FIG. 9 is a schematic view of the hitch mount.
The dotted lines are for purposes of illustrating a use and form no part of the claimed design.

1 Claim, 3 Drawing Sheets
